KEY-OPERATED PUSHBUTTON SWITCH
Alexander Feher, Jr., Bridgeport, Conn., assignor to General Electric Company, a corporation of New York
Filed May 23, 1961, Ser. No. 113,987
16 Claims. (Cl. 200—5)

This invention relates to an improved key-operated electric switch and particularly to a multiple pushbutton type switch having a plurality of keys for operating some of the pushrods thereof.

Pushbutton type switches have found widespread application as appliance switches for electric ranges, washing machines, dryers, room air conditioners, etc. In certain of these applications, it is highly desirable to have a low cost and efficient means for operating such a switch by the pivotal movement of actuating members such as keys, rather than by the manual depression of a pushrod. To enhance the appearance of the switch and make its manipulation very convenient, the keys used in such switches as these are sometimes relatively large in size. In switches of the prior art incorporating these relatively large keys, all of the keys have most commonly been mounted coaxially in relationship to each other, thereby necessitating a switch with a relatively elongated configuration. It has therefore been found desirable to provide a new and improved switch that is operable by relatively large keys, but has a substantially reduced length and a very compact configuration. It has been considered further desirable to provide a simple and improved means for transferring pivotal motion from certain keys of such a switch to a pair of adjacent pushrods. In addition, it has also been found desirable to obtain a novel means for controlling pivotal motion of these large sized keys, which means efficiently prevents any loose play thereof as they perform their selective pivoting functions.

The principal object of this invention is to provide a new and improved key-operated electric switch with a novel, efficient and compact means for obtaining actuation by relatively large keys.

A further object of this invention is to provide a key-operated electric switch which includes a multiple pushbutton type switch and an improved means for transferring motion from certain keys to associated pushrods of the switch to operate the switch.

An additional object of this invention is to provide a key-operated electric switch with an improved detent means for controlling the positioning of a pair of adjacent keys.

In carrying out one aspect of my invention, I apply it to a multiple pushbutton type switch mechanism including a plurality of contacts selectively operated by pushrods for controlling the contacts. The pushrods are arranged parallel to each other and in a row. By my invention, at least one pair of first and second opposed adjacent keys is arranged to operate a pair of associated first and second pushrods, respectively, by pivotal movement of the keys to their actuating positions in opposite directions of rotation. The keys are relatively large and cover a much greater expanse than the widths of the pushrods. The first key is pivotally mounted about an axis on one side of the row of pushrods and it overlies both of the pushrods. The second key is pivotally mounted about an axis parallel to the first-mentioned axis on the other side of the row of pushrods. The first key has an operating section overlying the first pushrod and is engageable therewith for selective depression of the first pushrod. A motion transfer lever underlies the first key and overlies the second pushrod to operate the second pushrod by pivotal movement of the lever in the same direction of rotation as the first key. The second key has an operat-

2

ing section overlying an outer end of the lever and engageable with the lever for selective depression of the second pushrod by transmission of actuating force from the second key to the second pushrod by the lever. Such an arrangement of the keys provides a compact key-operated pushbutton switch wherein efficient selective operation of the pushrods is achieved by movement of opposed adjacent keys in opposite rotary directions.

By a further aspect of my invention, I provide an improved detenting device for controlling the positioning of a pair of opposed actuating keys. This improved device may, of course, be combined with the aforesaid structure to provide a particularly desirable key-operated switch. My improved device is particularly applicable to a pair of keys arranged to pivot to their actuating positions in opposite directions of rotation, where the keys have oppositely disposed inner walls facing generally toward each other. The device includes a spring having a pair of specially formed resilient upright detent arms, and is disposed in the switch in generally underlying relationship to the inner walls of the pair of keys. One of the detent arms of the spring engages and coacts with a projection on the inner wall of an associated key to control the positioning of that key. The other detent arm engages and coacts with a projection on the inner wall of the other key to control the positioning thereof. Such an arrangement provides simplified and efficient control of the positioning of a pair of opposed keys by means of a single spring.

Further aspects of my invention will become apparent hereinafter, and the specification concludes with claims particularly pointing out and distinctly claiming the subject matter which I regard as my invention. The invention, as to organization and method of operation, together with further objects and advantages thereof, may best be understood by reference to the following description when taken in conjunction with the accompanying drawings, in which:

FIG. 1 is a top view partially broken away of an improved key-operated switch embodying my invention;

FIG. 2 is a front view of the switch, partially in section and partially broken away to show the internal actuating mechanism of the switch;

FIG. 3 is a partially exploded perspective view of the switch;

FIG. 4 is a fragmentary sectional view taken generally along the line 4—4 of FIG. 1;

FIG. 5 is an end view of the switch; and

FIG. 6 is a fragmentary end view of the switch, partially in section, to show the detenting arrangement for the switch keys.

Referring in detail to the drawings, and in particular to FIGS. 1 and 2, there is shown a key-operated switch 1 with which my invention has been advantageously employed. This particular switch 1 has been designed for use with an electric dryer apparatus and provides simplified and efficient operation of a pushbutton switch 3 by means of the selective pivoting motion of five relatively large sized switch actuating keys 5a-5e. Another key 5f is arranged to selectively actuate a sliding valve mechanism 7 for the dryer apparatus. For pivotally supporting the keys 5a-5f, together with pushbutton switch 3, in a compact over-all unit, mounting bracket 9 has been provided. The bracket 9 also supports the sliding valve mechanism 7, and a motion transfer arrangement for transmitting pivotal motion from certain of the large sized keys 5a-5f to pushbutton switch 3. The structure and operation of this motion transfer arrangement forms an important aspect of my invention and it shall be described in detail hereinafter.

Pushbutton switch 3 is of the multiple pushbutton type,

and, as shown in FIG. 2, it includes five pushrods 11, 12, 13, 14, and 15. All of the pushrods 11-15 are arranged in a row, as shown in FIG. 3, being disposed linearly and in parallel relationship. The pushrods 11-15 extend outwardly through appropriate apertures in top wall 17 of insulating body 19. Each pushrod 11-15 has a cylindrically curved actuating portion 21 formed at its innermost end to cooperate with various inclined upper working surfaces 23 formed in actuating recesses 25 of sliders 27. (See FIG. 2.) Sliders 27 selectively cooperate with actuating portions 21 of pushrods 11-15 in the well-known manner to provide a switch interlocking and actuating mechanism, the sliders being disposed in parallel side-by-side relationship to reciprocate longitudinally and actuate movable contact supporting arms 29. More particularly, the lower edge 31 of each slider, as shown in FIG. 2, has one or more cam surfaces 33 formed thereon for selectively engaging certain movable contact supporting arms 29. Longitudinal movement of each slider effects the opening and closing of predetermined contact pairs by camming one or more movable contact supporting arms 29 in certain operating position(s) of the slider.

The inclined working surfaces 23 of the sliders are so arranged on the different sliders that only one pushrod may be fully depressed at any one time. More specifically, to achieve switch interlocking, each pushrod actuating portion 21 extends into a group of generally aligned actuating recesses 25 of the sliders, as shown in FIG. 2, and cooperates with the working surfaces 23 thereof. For the pushrod return operation, one or more inclined surfaces 23 of certain slider recesses move longitudinally to engage portion 21 of the depressed pushrod and return it to its outermost position upon the subsequent depression of another pushrod. As is thus well known in the art, the depression of one of the pushrods 11-15 returns any previously depressed pushrod to its outermost position by coaction between one or more of the sliders and the previously depressed pushrod, and it also causes the longitudinal movement of one or more of the sliders for actuating one or more pairs of contacts of the switch by engagement of cam surfaces 33 of the sliders with movable contact supporting arms 29.

Turning now to the means for supporting the pushbutton switch 3, attention is directed to the structure of bracket 9 in FIG. 3. The mounting bracket 9 is generally flat, including platform 35 and longitudinally extensive parallel flanges 37 and 39 projecting upwardly from opposite sides of platform 35. (See FIG. 4.) Within platform 35, a series of rectangular openings 41, such as the ones shown representatively in FIG. 3, are positioned in row formation near flange 39 for receiving pushrods 11-15 of pushbutton switch 3. (See FIG. 3.) The row of openings 41 is generally parallel to flange 39, and the long axis of each of the openings 41 is generally perpendicular to flange 39. A pair of laterally spaced openings 43, such as the pair shown in FIG. 3, are positioned outwardly of the pushrod opening 41 at each end of the row of pushrod openings for receiving a pair of embossed ears 45 projecting outwardly from each upper end of switch body 19. For attaching pushbutton switch 3 to bracket 9, a pair of screws 47, such as the one shown in FIG. 3, are slipped through apertures 49 of platform 35 and tightened into threaded engagement with tapped holes 51 formed in the upper wall 17 of switch body 19. The pushbutton switch 3 is rigidly attached to the platform 35 of bracket 9, with pushrods 11-15 extending outwardly through apertures 41 (FIG. 4) and the longitudinal axis 52 (FIG. 3) of the pushbutton switch 3 generally parallel to flange 39 and spaced closer to flange 39 than to flange 37. (See FIG. 5.)

According to my invention, the switch 1 is actuated by a plurality of identical keys 5a-5e disposed in two parallel rows. An additional key 5f which manually controls sliding valve mechanism 7 is positioned in the end

5 of one of the rows to provide in the illustrated switch unit two parallel rows of three keys each (FIG. 1). More particularly, as shown in FIG. 1, the keys 5a, 5b, and 5c are in one row which overlies pushrods 11-15, and keys 5d, 5e, and 5f are in a second row offset from pushrods 11-15. The keys 5d, 5e, and 5f are also disposed in laterally opposite relationship, respectively, to keys 5a, 5b, and 5c. Thus, for example, key 5a is disposed in the row which overlies the pushrods 11-15, and key 5a is also in laterally opposite relationship to key 5d, which is in the row offset from the pushrods 11-15.

10 To pivotally support the keys 5a-5f, a series of parallel posts 53 are staked into slots formed in two rows on bracket 9. One row of these slots is adjacent to each of the flanges 37 and 39. The posts 53 of each row have 15 openings 54 (FIG. 3) which are in alignment so that two identical pivot rods 55 and 57 may be threaded through the posts without interference. Thus, as shown in FIG. 20, pivot rod 55 is disposed on one side of bracket 9 adjacent and generally parallel to flange 39 and platform 35. Pivot rod 57 is disposed on the other side of bracket 9 adjacent and generally parallel to flange 37 and platform 35. To secure pivot rods 55 and 57 upon their 25 associated posts 53, speed nuts 59 are fastened to the outer ends of the rods after the rods have been threaded into the post openings 54. (See FIG. 5.)

All of the keys 5a-5f have an enlarged rectangular box-shaped configuration with a hollow inner cavity 60 (FIG. 6). In particular, as shown in FIG. 3, each key 30 essentially includes handle section 61; rear wall 63; side walls 65, 67 which are perpendicularly disposed relative to handle section 61; and frontal wall 69. Handle section 61 is generally flat in overall appearance, but includes inwardly sloping surfaces 71, 73, 75, and 77 (as shown for the foreground key 5f of FIG. 3) which 35 conjunctively provide an indented actuating crease 79. Crease 79 is formed near and parallel to frontal wall 69, and is engaged by the finger tips for pivoting the key. The side walls 65 and 67 of the keys, which may be seen in 40 FIG. 3, have a vertical slot 81 which is formed upwardly from lower edge 83 near rear wall 63. Slot 81 includes a pair of arcuate bearing surfaces 85, and a pair of inwardly convex surfaces 87. The inwardly convex surfaces 87 are opposite to each other and are spaced 45 apart by a distance slightly less than the diameter of rods 55 and 57 so that the side walls 65 and 67 of each key may be conveniently snapped into position upon the rods.

The keys 5a-5f each also include a switch operating 50 projection 89 (FIG. 1) which extends downwardly from the inner surface of handle section 61 near frontal wall 69. Projection 89 has a bottom face 91 that slopes upwardly toward frontal wall 69, when the keys are viewed as shown in FIGS. 4-6. As shall be further described 55 hereinafter, keys 5a, 5b, and 5c overlie the outer ends of pushrods 11, 13, and 15. Slanted faces 91 of the projections 89 of the keys 5a, 5b, and 5c tangentially engage the curved outer ends of their associated pushrods to depress these pushrods to their actuated positions.

Considering further the structure of each of the keys 5a-5f, attention is directed to FIGS. 3, 4, and 5. Frontal wall 69 of each of the keys is sloped downwardly and away from rear wall 63 (viewing FIG. 4). Near bottom edge 93 of frontal wall 69, an actuating nose 95 is 60 formed. Nose 95 projects downwardly and outwardly away from bottom edge 93 and includes a longitudinally extensive curved actuating surface 96 (FIG. 4). As shall be further described hereinafter, noses 95 of the keys 5d and 5e overlie the outer ends of pivoted motion transmitting levers 97 to selectively actuate pushrods 12 and 14 by pivotal motion of keys 5d and 5e.

65 As shown in FIG. 1, keys 5a, 5b, and 5c are pivotally and coaxially mounted in side-by-side relationship on rod 55 for movement toward their depressed positions in the same direction of rotation. For example, key 5c, as shown

on the right side of FIG. 5, pivots to its depressed position in a counterclockwise direction of rotation about its axis. The keys 5a and 5b in like manner also pivot to their depressed positions in this same direction of rotation. Projections 89 of the keys 5a, 5b, and 5c overlie the pushrods 11, 13, and 15, respectively, and directly actuate these pushrods when the keys 5a, 5b, and 5c are selectively depressed.

As further shown in FIG. 1, keys 5d, 5e, and 5f are pivotally and coaxially mounted in side-by-side relationship on rod 57 for movement toward their depressed positions in the same direction of rotation. However, the direction of rotation for movement of keys 5d, 5e, and 5f to their depressed positions is directly opposite to the direction of rotation for movement of keys 5a, 5b, and 5c to these positions. For example, key 5f, as shown on the left side of FIG. 5, pivots to its depressed position in a clockwise direction of rotation about its axis, which direction is opposite to the counterclockwise direction of rotation for similar movement of its laterally opposite key 5c.

To expeditiously transmit the pivotal motion of keys 5d and 5e to pushrods 12 and 14, respectively, by means of my invention, the levers 97 have been provided. Levers 97 are shaped like shallow channels (FIG. 4) and each includes a tab 99 turned angularly upwardly from end 101 (FIG. 6). The tab 99 of each lever 97 is extended through a slot 103 (FIG. 3) of bracket flange 39, to pivotally support the lever 97 thereupon. As shown in FIGS. 1 and 5, levers 97 are elongated, and each lever extends transversely to the platform 35 as well as to the longitudinal axis of pushbutton switch 3. In particular, one of the levers 97 extends underneath the entirety of key 5a and overlies the curved outer end of pushrod 12. The free end 105 of the lever 97 which extends underneath key 5a is disposed directly underneath the actuating nose 95 of key 5d. The other one of the levers 97 extends underneath the entirety of key 5b and overlies the curved outer end of pushrod 14, as shown in FIG. 4. The free end 105 of the lever 97 which extends underneath key 5b is disposed directly underneath the actuating nose 95 of key 5e.

Levers 97 are mounted in their slots 103 on bracket flange 39 for pivotal movement toward platform 35 in the same direction of rotation as the keys 5a and 5b. To control vibrations between levers 97 and their associated pushrods 12 and 14, a wire 107 is strung on the outside of flange 39 through downwardly facing tabs 109 of flange 39 and upwardly facing tabs 99 of the two levers (FIGS. 3 and 4). Wire 107 thus assumes an undulatory configuration, as shown in FIG. 3, and normally biases the free ends 105 of the levers 97 upwardly and away from their associated pushrods 12 and 14 (FIG. 4).

For an explanation of the operation of pushbutton switch 3 by the keys 5d and 5e, attention is directed to FIG. 4, wherein the laterally opposed keys 5b and 5e are illustrated. Switch operating projection 89 of key 5b, as shown in FIG. 4, is disposed behind pushrod 14 and it overlies pushrod 13. (See also FIG. 1.) When key 5b is depressed, the sloped face 91 of its projection 89 rotates through an arc drawn about the axis of rotation of key 5b. Face 91 of key 5b thus moves through this arc for a particular appropriate arcuate length required to completely depress pushrod 13. The curved actuating surface 96 of key 5e normally engages the flat upper surface of the free end 105 of lever 97; and when key 5e is depressed, surface 96 thereof forces the lever 97 to pivot downwardly and depress pushrod 14. When key 5e is depressed, the actuating surface 96 of nose 95 (which is farther away from its axis of rotation than is projection 89 of key 5e) rotates through an arc drawn about the axis of rotation of key 5e. The curved actuating surface 96 of key 5e thus moves through this arc for an arcuate length considerably greater than the arcuate length through which face 91 of key 5b moves to its

actuated position. However, in view of the pivotal mounting and disposition of lever 97, when key 5e is depressed, the inner flat surface of the lever 97 overlies and is engageable with pushrod 14, rotates about its axis (i.e., tab 99 at slot 103) for an arcuate length approximately equivalent to the arcuate length of movement for projection 89 of key 5b. It will therefore be seen that lever 97 imparts motion to pushrod 14 which is substantially equivalent to the motion imparted to pushrod 13 by key 5b. Such a motion transmission arrangement for the transversely offset keys 5d and 5e effectively and substantially equalizes the forces imposed upon the pushrods by the keys 5a-5e of the switch, and thereby enhances efficient switch operation.

The key 5d operates in essentially the same manner as described for key 5e, except that the pivotal actuating motion of key 5d is transmitted by its associated lever 97 to pushrod 12.

Turning now to a further aspect of the present invention which concerns itself with an improved means for minimizing loose play of the keys and controlling the pivotal motion thereof, attention is directed to FIGS. 3 and 6. Between the two rows of keys 5a, 5b, 5c, and 5d, 5e, 5f, a U-shaped center rail 111 is positioned on bracket 9. More particularly, rail 111 includes two opposed vertical ends 113 (FIG. 3) which are attached to bracket platform 35 by screws 115, such as the one shown in FIG. 3. Elongated section 117 of rail 111 has opposed sides 119 which curve upwardly and away from each other abruptly near flat outer longitudinal surface 121 (as shown in FIG. 5). Shoulder 123 of each of the actuating noses 95 of keys 5a-5f engages the underside ledge 125 (FIG. 4) of rail section 117 to limit the pivotal motion of the keys at their outer or undepressed positions after they have been returned thereto from their depressed positions. Underneath the underside of rail section 117 between each pair of laterally disposed keys, a double detent spring 127 is positioned on bracket 9. (See FIGS. 3 and 6.)

The spring 127 includes a generally flat basal section 129 which is riveted to platform 35, and a pair of laterally and longitudinally offset resilient arms 131 and 132. Resilient arms 131 and 132 are arranged to continuously engage and control associated keys during the pivotal movement of the keys. The arms 131 and 132 are each bent upwardly and inwardly from basal section 129 (as shown in FIG. 6) and then bowed outwardly to form intermediate groove 133 and convex outer face or cheek 135. The free end 137 of each of the arms 131 and 132 is then turned back outwardly to provide an outer groove 139.

Turning now to an explanation of how the double detent springs 127 control the positioning of each laterally opposed pair of keys, attention is directed in particular to FIG. 6. Each of the keys 5a-5f has a special detent lip 141 formed on the bottom edge 93 of frontal wall 69. (See also FIG. 3.) Lip 141 is formed on each key next to actuating nose 95 (FIG. 3), and the inner longitudinal end 141a of the lip is located approximately at the longitudinal center of frontal wall 69. With the lips 141 formed on the identical keys 5a-5f in this manner, the lips 141 of laterally opposed keys, such as, for example, the keys 5c and 5f, present laterally and longitudinally offset projecting surfaces for coaction with the resilient arms 131 and 132 of double detent spring 127. More particularly, in viewing FIG. 6, lip 141 of key 5f is disposed opposite to and coacts with resilient arm 132 of double detent spring 127, and lip 141 of key 5c is disposed opposite to and coacts with resilient arm 131 of spring 127. With the arms of spring 127 disposed in this manner, the detent lip 141 of each laterally opposite key rides along the outer surface of an associated resilient arm, and the spring forces imparted to the detent lip 141 during pivotal movement thereof by its associated resilient arm accurately control the positioning of each key.

To further explain the operation of detent spring 127 in conjunction with keys 5a-5f of my improved switch, attention is directed to FIG. 6. When key 5c is in its outer or undepressed position, where it is shown in FIG. 6, the bottom outer edge of lip 141 rests at the top of convex outer face 135 at or near outer groove 139. Lip 141 of key 5c is then biased into that position by resilient force imparted thereto by arm 131. In particular, the curvature of face 135 of arm 131 acts on lip 141 to hold key 5c in its outer position. When one of the keys 5a-5f is depressed, the curvature of face 135 of the associated detent spring arm initially resists the pivotal motion of the key to provide the desired control thereof. When the depressed key, such as key 5f in FIG. 6, has reached its innermost position, the bottom outer edge of lip 141 is engaged by the upwardly and inwardly inclined bottom surface of arm 132. The flat and inclined bottom surface of arm 132 then moves resiliently outwardly and cams key 5f to its normal depressed position, where key 5f is shown in FIG. 6. The upper outer edge of lip 141 then engages underneath the bottom of convex outer face 135 at or near intermediate groove 133 and the curvature of face 135 holds key 5f in its normal depressed position. Biasing force imparted to lip 141 of key 5f by arm 132 thus retains key 5f in its normal depressed position (FIG. 6).

It will now therefore be seen that each of the double detent springs 127 of my improved switch 1 coacts upon a laterally opposed pair of keys to efficiently control the positioning of each of the keys.

To enable key 5f of my improved switch 1 to mechanically operate the sliding valve mechanism 7, selective latching device 143 has been provided. (See FIG. 2.) Device 143 includes a cylindrically configured housing 145 (FIG. 2) with flanges 147 (FIG. 3) formed near one of its ends for attachment to an L-shaped valve bracket 149 of valve mechanism 7. Driving plunger 151 of device 143 extends into housing 145 and selectively engages a ratchet mechanism (not shown) in the housing to first move the driven plunger 153 downwardly (viewing FIG. 5) and hold it in its depressed position when plunger 151 is released. The next time driving plunger 151 is depressed, it acts upon the ratchet mechanism to release driven plunger 153 and allow it to be returned to its original position. Turning now to the sliding valve mechanism, the L-shaped bracket 149 has a flow sleeve 154 (FIG. 2) mounted perpendicularly near its bottom and a lanced post 155 for supporting the bottom of housing 145. Slide 159 moves along bracket 149 within guiding tabs 160 thereof (FIGS. 3 and 5), and has a projecting platform 157 which extends through slot 161 of bracket 149. The slide 159 also has a flow sleeve 162 fastened perpendicularly to its outer face. Sleeve 162 becomes axially aligned with sleeve 154 of bracket 149 when slide 159 is in its depressed position to allow the flow of a fluid through the two sleeves. Driven plunger 153 of device 143 extends through post 155 and its bottom rests upon projecting platform 157. To continuously bias slide 159 upwardly along the juxtaposed face of bracket 149, tension spring 158 has one of its ends connected to platform 157 and the other end is connected to the upper section of bracket 149. Spring 158 thus runs in tension to bias slide 159 into the position where it is shown in FIG. 2. When slide 159 is in this position, the flow sleeves 154 and 162 are in vertically offset relationship and passage of a fluid through the sleeves is blocked by interrupting wall surfaces of bracket 149 and slide 159.

For an explanation of the specific mode of operation of valve mechanism 7 as is achieved by the action of key 5f upon the selective latching device 143, attention is directed to FIGS. 2 and 5. When key 5f is in its outer or undepressed pivotal position, the slanted face 91 of actuating projection 89 overlies driving plunger 151 and is spaced vertically therefrom. When driving plunger

151 is in the position where it is shown in FIG. 5, the driven plunger 153 engages platform 157 of slide 159 to hold flow sleeve 162 of the slide downwardly against the biasing force of tension spring 158. When valve mechanism 7 is in this position, the flow sleeve 162 of slide 159 is vertically offset from flow sleeve 154 of bracket 149 and flow is blocked through the sleeves by opposing walls of the slide and bracket, respectively.

When key 5f is depressed from the position which it assumes in FIG. 5, driving plunger 151 is pushed downwardly by face 91 of projection 89 to its dotted position 151a, and driven plunger 153 is moved downwardly to dotted position 153a. As driven plunger 153 moves to position 153a, it drives platform 157 with it, and slide 159 thus moves downwardly within tabs 160. As the slide 159 moves along the contiguous face of bracket 149, flow sleeve 162 thereupon moves into alignment with flow sleeve 154 to allow fluid communication through the sleeves. Latching device 143 holds driven plunger 153 in position 153a until the next time driving plunger 151 is depressed. After valve mechanism 7 has thus been opened by the depression of key 5f, it is closed the next time the key 5f is depressed. More particularly, when driving plunger 151 is in position 151a, the next time it is depressed by key 5f, it is released by latching device 143 and returns to its original position along with driven plunger 153. When driven plunger 153 returns to its original position, where it is shown in full in FIG. 5, spring 158 acts upon slide 159 to return it to the closed position. Flow sleeves 154 and 162 are then out of communication to block the flow therethrough.

The key 5f therefore combines with selective latching device 143 and valve mechanism 7 to provide a simple and efficient key-operated valve which is built into my improved switch 1.

It will now therefore be seen that my new and improved key-operated switch as herein illustrated provides an efficient and compact means for obtaining key-operated control of a multiple pushbutton switch. It will further be realized that my new and improved switch achieves a novel and simplified structure for controlling a switch by a pair of laterally opposed keys. It should be understood that certain aspects of my invention may be incorporated beneficially and efficiently in other various types of pushbutton switch applications.

While in accordance with the Patent Statutes, I have described what at present is considered to be the preferred embodiment of my invention, it will be obvious to those skilled in the art that various changes and modifications may be made therein without departing from my invention, and I therefore aim in the following claims to cover all such equivalent variations as fall within the true spirit and scope of this invention.

What I claim as new and desire to secure by Letters Patent of the United States is:

1. A key-operated switch comprising a multiple pushbutton type switch mechanism having a plurality of contacts and means including at least one pair of parallel pushrods for operating the contacts, and means for operating said pushrods comprising first and second relatively wide keys pivotally mounted about separate parallel axes disposed on opposite sides of said pushrods for pivotal movement to their respective actuating positions in opposite rotary directions, said first key including an operating section overlying one of said pushrods and engageable therewith for selective depression of the associated pushrod, a pivoted lever at least partially underlying said first key and overlying the other of said pushrods, said second key including an operating section overlying a portion of said lever and engageable with said lever for selective depression of the last-mentioned pushrod by said lever, whereby said first and second keys pivot about their axes in opposite directions of rotation to selectively and efficiently operate said pushrods.
2. A key-operated switch comprising a multiple push-

button type switch mechanism having a plurality of contacts and means including at least one pair of parallel pushrods arranged in a row for operating the contacts, and means for operating said pushrods comprising first and second keys pivotally mounted about separate parallel axes disposed on opposite sides of said pushrods for pivotal movement to their respective actuating positions in opposite rotary directions, said keys being relatively wide and covering a much greater expanse than the widths of the pushrods, said first key overlying both of said pushrods and including an operating section overlying one of said pushrods, the operating section of said first key being engageable with said one pushrod for selective depression of said pushrod, a pivoted lever underlying said first key and overlying the other of said pushrods, said second key including an operating section overlying an outer end of said lever and engageable with said lever for selective depression of the last-mentioned pushrod by said lever, whereby said first and second keys pivot about their axes in opposite directions of rotation to selectively and efficiently operate said pushrods.

3. A key-operated switch comprising a multiple push-button type switch mechanism having a plurality of contacts and means including at least one pair of parallel pushrods for operating the contacts, and means for operating said pushrods comprising first and second relatively wide keys pivotally mounted about separate parallel axes disposed on opposite sides of said pushrods for pivotal movement to their respective actuating positions in opposite rotary directions, said first key including an operating section overlying one of said pushrods and engageable therewith for selective depression of the associated pushrod, a pivoted lever overlying the other of said pushrods and mounted on an axis adjacent the axis of said first key, said second key including an operating section overlying a portion of said lever and engageable with said lever for selective depression of the last-mentioned pushrod by said lever, whereby said first and second keys pivot about their axes in opposite directions of rotation to selectively and efficiently operate said pushrods.

4. A key-operated switch comprising a multiple push-button type switch mechanism having a plurality of contacts and means including at least one pair of parallel pushrods for operating the contacts, and means for operating said pushrods comprising first and second relatively wide keys pivotally mounted about separate parallel axes disposed on opposite sides of said pushrods for pivotal movement to their respective actuating positions in opposite rotary directions, said first key including a downwardly protruding operating section overlying one of said pushrods and located between the axis of said first key and the front end thereof, said operating section being engageable with said one pushrod for selective depression of the associated pushrod, a pivoted lever at least partially underlying said first key and overlying the other of said pushrods, said second key including a downwardly protruding operating section at the front end thereof spaced laterally from the operating section of said first key, said last-mentioned operating section overlying a portion of said lever and engageable with said lever for selective depression of the last-mentioned pushrod by said lever, whereby said first and second keys pivot about their axes in opposite directions of rotation to selectively and efficiently operate said pushrods.

5. A key-operated switch comprising a multiple push-button type switch mechanism having a plurality of contacts and means including at least one pair of parallel pushrods arranged in a row for operating the contacts, and means for operating said pushrods comprising first and second keys pivotally mounted about separate parallel axes disposed on opposite sides of said pushrods for pivotal movement to their respective actuating positions in opposite rotary directions, said keys being relatively wide and covering a much greater expanse than the widths

of the pushrods, said first key overlying both of said pushrods and including an operating section overlying one of said pushrods, the operating section of said first key being engageable with said one pushrod for selective depression of said pushrod, a pivoted lever underlying said first key and overlying the other of said pushrods, spring means biasing said lever away from said other pushrod and toward the underside of said first key, and said second key including an operating section overlying an outer end of said lever and engageable with said lever for selective depression of the last-mentioned pushrod by said lever, whereby said first and second keys pivot about their axes in opposite directions of rotation to selectively and efficiently operate said pushrods.

6. A key-operated switch comprising a multiple push-button type switch mechanism having a plurality of contacts and means including at least one pair of parallel pushrods arranged in a row for operating the contacts, and means for operating said pushrods comprising first and second keys pivotally mounted about separate parallel axes disposed on opposite sides of said pushrods for pivotal movement to their respective actuating positions in opposite rotary directions, said keys being relatively wide and covering a much greater expanse than the widths of the pushrods, said first key overlying both of said pushrods and including an operating section overlying one of said pushrods, the operating section of said first key being engageable with said one pushrod for selective depression of said pushrod, a mounting bracket for said switch mechanism and said keys, a pivoted lever having a tab at one end thereof extending through an aperture in said mounting bracket, said lever underlying said first key and overlying the other of said pushrods, a spring wire engaging said tab and biasing said lever away from said other pushrod and toward the underside of said first key, and said second key including an operating section overlying the end of said lever remote from said tab and engageable with said lever for selective depression of the last-mentioned pushrod by said lever, whereby said first and second keys pivot about their axes in opposite directions of rotation to selectively and efficiently operate said pushrods.

7. A key-operated switch comprising a multiple push-button type switch mechanism having a plurality of contacts and means including a plurality of parallel pushrods arranged in a row for operating the contacts, and means for operating said pushrods comprising first and second rows of keys pivotally mounted about separate parallel axes disposed on opposite sides of said pushrods for pivotal movement to their respective actuating positions in opposite rotary directions, said keys being relatively wide and covering a much greater expanse than the widths of the pushrods, the keys of said first row overlying said pushrods and each including an operating section engageable with one of said pushrods, the operating sections of the keys in said first row being engageable with their respective pushrods for selective depression thereof, a plurality of pivoted levers each underlying one of the keys in said first row and overlying a pushrod not engageable by said keys in said first row, the keys of said second row each including an operating section overlying the outer end of one of said levers and engageable with said lever for selective depression of the pushrod associated therewith, whereby the keys in said first and second rows pivot about their axes in opposite directions of rotation to selectively and efficiently operate said pushrods.

8. A key-operated electric switch comprising a base, a plurality of contacts and means including at least one pair of oppositely disposed keys for operating the contacts, said keys having oppositely disposed walls which face toward each other and being pivotally mounted for movement on said base in opposite directions of rotation, and a detent spring having two detenting sections, means whereby each of said detenting sections has independent

movement with respect to said other section and engages with a respective one of said walls of said keys thereby to separately control the positioning of said keys.

9. A key-operated electric switch comprising a plurality of contacts and means including at least one pair of oppositely disposed keys for operating the contacts, said keys having oppositely disposed walls having lips which face toward each other, and being arranged to pivot in opposite directions of rotation, and a detent spring means engageable with said lips thereby to control the positioning of said keys, said spring means including a pair of arms engageable respectively by said lips, each of said arms including a pair of grooves for defining the upper and lower positions of said keys and an outwardly curved section between said grooves facilitating the engagement of said lips in said grooves.

10. A key-operated switch comprising a multiple pushbutton type switch mechanism having a plurality of contacts and means including at least one pair of parallel pushrods for operating the contacts, and means for operating said pushrods comprising first and second relatively wide keys pivotally mounted about separate parallel axes disposed on opposite sides of said pushrods for pivotal movement to their respective actuating positions in opposite rotary directions, said first key including an operating section overlying one of said pushrods and engageable therewith for selective depression of the associated pushrod, a pivoted lever at least partially underlying said first key and overlying the other of said pushrods, said second key including an operating section overlying a portion of said lever and engageable with said lever for selective depression of the last-mentioned pushrod by said lever, whereby said first and second keys pivot about their axes in opposite directions of rotation to selectively and efficiently operate said pushrods, said keys each including a detent lip on the outer edge thereof, and spring means engageable with said lips to control the positioning of said keys, said spring means comprising a separate spring arm for each of said keys, with each spring arm including a pair of grooves defining the upper and lower positions of the associated key and an outwardly curved section between said grooves for facilitating the engagement of said lips in said grooves.

11. A key-operated electric switch comprising a plurality of contacts and means including at least one pair of oppositely disposed keys for operating the contacts, said keys having oppositely disposed walls having lips which face toward each other and are laterally spaced apart, said keys being arranged to pivot in opposite directions of rotation, and an integral detent spring engageable with said walls of said keys thereby to control the positioning of said keys, said spring having a base portion and a pair of laterally spaced arms projecting upwardly from said base portion and engageable respectively by said lips, each of said arms including a pair of grooves for defining the upper and lower positions of said keys, an outwardly curved portion between said grooves for facilitating the engagement of said lips in said grooves, and a slanted portion between said base portion and the lower of said grooves to return said key to said lower groove upon overtravel of said key beyond said groove.

12. A key-operated switch comprising a multiple pushbutton type switch mechanism having a plurality of contacts and means including at least one pair of parallel pushrods for operating the contacts, and means for operating said pushrods comprising first and second relatively wide keys pivotally mounted about separate parallel axes disposed on opposite sides of said pushrods for pivotal movement to their respective actuation positions, said first key including an operating section overlying one of said pushrods and engageable therewith for selective depression of the associated pushrod, a pivoted lever overlying the other of said pushrods, said second key including an operating section engageable with said lever for selective depression of the last-mentioned pushrod by said

lever, whereby said first and second keys pivot about their axes to selectively and efficiently operate said pushrods.

13. In a key-operated unitary appliance control panel, a mounting bracket, a multiple pushbutton switch providing electrical control functions and having a plurality of pushrods aligned in a single row secured to said mounting bracket, said multiple pushbutton switch being secured to said mounting bracket, first and second rows of keys for actuating said pushrods, said rows of keys being mounted adjacent to one another and pivotally mounted about separate parallel axes on said mounting bracket, with the keys of said first row having an operating section for actuating their associated pushrods directly and the keys of said second row spaced from their associated pushrods, lever means engageable by said keys in said second row, said lever means engageable with their associated pushrods, said keys actuating said pushrods through said lever means which are engageable with said pushrods, a separate mechanism for controlling a mechanical function mounted on said mounting bracket, said separate mechanism being disposed underneath one of said keys in said second row, said pushrods spaced laterally from said separate mechanism, and said separate mechanism including an actuating member having means engaged by said one key, whereby said panel is effective to control both electrical functions and a mechanical function.

14. In a unitary appliance control panel, a mounting bracket, a multiple pushbutton switch providing electrical control functions and having a plurality of pushrods aligned in a single row, said multiple pushbutton switch being secured to said mounting bracket, first and second rows of keys in actuating engagement with said pushrods, said rows of keys being mounted adjacent to one another on said mounting bracket, means connecting said keys in each of said rows of keys in actuating engagement with said aligned pushrods, and a valve mechanism supported on said bracket and spaced laterally from said pushrods, said valve mechanism disposed underneath one of said keys for actuation thereby, said valve mechanism including an actuating plunger engaged by said one key and means connected to said plunger whereby said actuator is effective to open said valve mechanism upon a first operation of said one key and to close said valve mechanism upon the next operation of said one key, whereby said unitary panel is effective to provide both electrical control functions and a flow regulating function.

15. In a unitary appliance control panel, a planar mounting bracket having an upper and a lower face, a multiple pushbutton switch for providing electrical control functions and having a plurality of pushrods aligned in a single row secured to the lower face of said mounting bracket, a plurality of actuators in actuating engagement with said pushrods, said actuators being secured to the upper face of said mounting bracket in at least two parallel rows, said rows being adjacent to one another, means connecting said actuators in each of said rows of actuators in actuating engagement with said aligned pushrods, and a valve mechanism spaced laterally from said pushrods and secured to the lower face of said bracket, said valve mechanism mounted under one of said actuators in one of the rows for operation thereby, and said valve mechanism including a movable plunger engaged by said one actuator and means connected to said plunger whereby said actuator is effective to open said valve mechanism upon a first operation of said one actuator and to close said valve mechanism upon the next operation of said one actuator, whereby said unitary panel is effective to provide both electrical control functions and a flow regulating function.

16. A key-operated switch and valve control for a dryer, comprising a multiple pushbutton type switch mechanism having a plurality of contacts and means including a plurality of aligned pushrods for operating said contacts; a valve mechanism including a stationary flow

sleeve, a movable flow sleeve arranged for movement into and out of registry with said stationary flow sleeve and a motion transfer means including an input plunger for operating said movable flow sleeve; bracket means mounting said switch mechanism and said valve mechanism in a laterally spaced arrangement; and first and second rows of keys for operating said pushrods of said switch mechanism and said input plunger of said valve mechanism, said rows of keys being pivotally mounted about separate parallel axes disposed on opposite sides of said pushrods for pivotal movement to their respective actuating positions in opposite rotary directions, the keys of said first row each including an operating section engageable with one of said pushrods, a plurality of levers each overlying a pushrod not engageable by the keys in said first row, the keys in said second row including operating sections for respectively engaging and operating said levers to depress the pushrods associated therewith, and one of the keys in said second row having an operating section for

engaging said plunger to actuate said movable flow sleeve, whereby said rows of keys are effective to control both said switch mechanism and said valve mechanism.
